UNITED STATES PATENT OFFICE.

WILBUR HAYNE, OF OTTAWA, ILLINOIS.

ACETYLENE-GAS GENERATOR.

1,078,046.

Specification of Letters Patent. Patented Nov. 11, 1913.

Application filed March 4, 1912. Serial No. 681,585.

To all whom it may concern:

Be it known that I, WILBUR HAYNE, a citizen of the United States, residing at Ottawa, in the county of La Salle and State of Illinois, have invented a new and useful Acetylene-Gas Generator, of which the following is a specification.

This invention has reference to improvements in acetylene gas generators, and its object is to provide a generator wherein the gas generated is filtered and cooled, the residue from the hydrated carbid is readily removable without disturbing the water contained in the generator and without contaminating such water, and an emergency supply of calcium carbid is provided to be used on the exhaustion of the main supply.

The invention comprises a suitable tank inclosing a bell capable of rising and falling within the tank in accordance with the amount of gas therein with a carbid container or reservoir within the same tank and interior to the bell, said carbid container having associated therewith an emergency container for carbid, which for purposes of accessibility may be carried by the gas bell, while in line with the discharge end of the carbid container there is a receptacle for the residue, which receptacle may be readily removed when filled without contamination of the water used to hydrate the carbid, and, furthermore, there is provided within the casing or tank a gas receptacle communicating with the gas bell and immersed in the water in the tank or casing, from which receptacle the gas is led by suitable piping to the point of consumption.

The invention will be best understood from a consideration of the following detailed description, taken in connection with the accompanying drawings forming a part of this specification, with the further understanding that while the drawings illustrate a practical embodiment of the invention it is susceptible of other practical embodiments, wherefore the invention is not confined to any strict conformity with the showing of the drawings, but may be variously modified so long as such modifications mark no material departure from the salient features of the invention.

In the drawings:—Figure 1 is a vertical diametrical section of the improved generator with some parts in elevation. Fig. 2 is a fragmentary elevation with parts in section of the upper portion of the generator showing a phase in the operation thereof.

Fig. 3 is a section on the line 3—3 of Fig. 1 with some parts omitted. Fig. 4 is a section on the line 4—4 of Fig. 1. Fig. 5 is a section on the line 5—5 of Fig. 1 with distant parts omitted. Fig. 6 is a detail vertical section of the emergency or auxiliary carbid container. Fig. 7 is a detail vertical section of the gas strainer.

Referring to the drawings, there is shown a casing 1 which may be in the form of a cylinder, although the particular shape of this casing is not mandatory. The casing 1 constitutes the main casing of the apparatus and is usually made tall with respect to the lateral extent of the casing. Applied to the top of the casing is a cap member 2 having an axially extended dome portion 3, which latter may be omitted if the casing be made tall enough.

The casing 1 is provided with a bottom member 4 and within the casing close to the bottom member there is lodged an annular drum 5 mounted upon feet or supports 6 resting on the bottom 4. The drum 5 is designed to constitute a reservoir or container for generated gas, and from this drum there leads a pipe 6^a to the exterior of the casing 1, and is designed to be connected to the distribution installation. The drum 5 has its inner wall 7 in surrounding relation to a chamber 8, while the bottom wall of the drum may be extended to constitute the bottom of the chamber 8, although this feature is not mandatory. Secured to the inner wall 7 of the drum 5 are uprights 9 arranged in a substantially circular series, and at intervals these uprights are connected by bands 10, so that the uprights and bands form an elongated cage arranged axially with reference to the tank or casing 1. The cage made up of the uprights 9 and bands 10 is designed to support a carbid receptacle 11, which may be cylindrical in cross section when the cage is of such shape, and this receptacle 11 is formed on its exterior at a point between the ends with an outstanding flange 12 designed to rest upon the upper ends of the uprights 9, it being understood that all expressions of position have relation to the installed apparatus.

That end of the carbid container 11 constituting the lower end thereof is tapered to a neck 13, and this neck has hinged thereto a gate 14, one end of which gate serves as a valve for normally closing the neck 13 against the escape of carbid from the container 11. That end of the gate 14 remote

from the neck 13 and on the opposite side of the hinge from the neck 13 is provided with a weight 15 sufficient to hold the gate against the neck.

5 Within the carbid container 11 are spaced braces 16 serving as guides for an axially disposed rod 17 normally resting against the gate 14, the said rod extending through the neck 13. This rod projects above the upper 10 end of the container 11, which end is open, and adjacent the neck 13 the rod carries a deflector 18 which may also act as a stop to prevent more than a limited movement of the rod 17 in a direction to open the valve or 15 gate 14.

Within the chamber 8 there are supports 19 for a receptacle 20 adapted to move lengthwise of the cage defined by the uprights 9, and this receptacle is provided 20 with a handle 21 which may be reached through the upper end of the cage when the carbid receptacle is removed. Carried by the cage adjacent the upper end of the receptacle 20 when seated on the supports 19 25 is a tapering deflector or funnel 22, designed to direct carbid residue into the receptacle 20.

Within the casing 1 and of somewhat less diameter than the internal diameter of said 20 casing is a gas bell 23, of a length to reach with its open end comparatively close to the chamber 5 and having an upper end 24 normally closed, while to facilitate the rise and fall of the bell guide rollers 25 are provided 35 on the upper end 24. The bell carries a cylinder 26 in concentric relation to the walls of the bell and supported by and extending through the top 24, the cylinder 26 being of a size to embrace the cage made up 40 of the uprights 9 and bands 10. The cylinder 26 is open at both ends, and above the top 24 is provided with a cap member 27, the said cap member and corresponding end of the cylinder being screw-threaded, so that 45 the cap member may be screwed tight on the cylinder 26, and to prevent leakage the cap member 27 is provided with a peripheral flange 28, while the cylinder 26 has a matching flange 29, between which flanges there 50 is introduced a gasket 30 of suitable packing material. Extending from and communicating with the interior of the cylinder 26 is a pipe 31, which pipe in the particular construction shown is carried through and 55 above the top 24 and then again through the top 24 into the interior of the bell 23, and where this pipe is above the top 24 it is provided with a cut-off valve 32. The bell is also provided with another valve 33 carried by the top 24, whereby the interior of the bell may be placed in communication with the space above the bell. The cap 27 also carries a valve 34 similar to the valve 33 for placing the interior of the cylinder 60 26 in communication with the space above it.

Supported by the cap 27 is a container 35 opening through the cap 27 and above the same provided with a cover member 36. The lower end of the chamber 35 is closed except for a central passage 37 normally closed by a valve 38 on one end of a rod 39 extending through the cap 36 and accessible above the same.

In the upper end of the carbid receptacle 11 there is formed a small chamber 40 having an opening 41 therein, and the chamber 40 is of a size to receive the container 35, while the opening 41 is in line with the opening 37.

The top wall of the chamber 5 carries a pipe 42 extending well up into the bell 23 and at the upper end carries a strainer casting 43 provided with a perforated cap 44 and containing a mass 45 of suitable fibrous material. The chamber 5 is also provided 85 with a drain valve 46, whereby water of condensation which may accumulate within the chamber 5 may be drawn off from time to time.

Let it be assumed that the apparatus has 90 been installed, then the operator introduces water into the casing 1 until it reaches a level about that indicated at 47, although this particular level is not at all mandatory. To introduce the water the cap 2 is 95 first removed, and by allowing the valve 33 to remain open the bell 23 will sink to its lowest operative point. The cap 27 is also removed and the carbid container 11 is filled to the desired extent. Furthermore, the cap 36 is removed and the container 35 is filled with carbid, this container 35 constituting a receptacle for an emergency or auxiliary quantity of carbid for use when the main supply has become exhausted, and it is not at the time expedient to introduce a further supply in the main receptacle 11. If the valve 33 be allowed to remain closed until after the carbid has been introduced into the receptacle 11 and 100 the cap 27 has been placed in position, the bell 23 will not at once sink to its lowest level, so that after the caps 27 and 36 have been placed in position the valve 33 may be opened to allow escape of imprisoned 105 air and the consequent sinking of the bell 23 to its lowest level. This will bring the cap 27 into engagement with the upper end of the rod 17, and the weight of the bell and parts carried thereby being sufficient 110 to overcome the weight 15 will cause an opening of the valve 14 and the escape of an appropriate quantity of carbid 11, which is directed into the water then within the casing 1 and to localize the fall of carbid 115 into the water there is provided a funnel 48 below the neck 13. The carbid on falling into the water generates acetylene gas, which rises into the cylinder 26 and when the pressure within the cylinder 26 has 120 125 130

risen sufficiently the gas will find its way into the interior of the bell 23, thus ultimately lifting the bell until the cap 27 no longer rests upon the rod 17 and the weight 5 15 is enabled to close the valve 14, thus preventing further escape of carbid. The spent carbid is directed by the guide or funnel 22 into the receptacle 20. Suppose that the acetylene is being utilized 10 through the pipe 6^a, the chamber 5 to which the pipe 6^a connects is constantly replenished from the supply of acetylene within the bell 23, such supply being filtered through the material 45, so that clean gas 15 reaches the chamber 5. As the gas is used up the bell sinks until the cap 27 engages the rod 17, and another supply of carbid is furnished to the water, to be converted 20 into gas. This operation will continue automatically until the supply of carbid within the receptacle 11 is exhausted, it being assumed that the supply has not been replenished. The exhaustion of the carbid will be readily observed by the dimming of 25 the lights supplied by the generator, and the operator will then know that a further supply of carbid is necessary. As the exhaustion of the carbid is liable to take place at night time when it is inconvenient or dangerous to place more carbid in the generator, the operator has but to remove the cap 2, which operation will not permit the escape of any material amounts of gas, and then by manipulating the rod 39 the valve 35 38 is opened and the contents of the receptacle 35 permitted to gravitate into the chamber 40 from whence the carbid readily escapes into the receptacle 11, and so replenishes the latter to a limited extent, the 40 size of the auxiliary receptacle 35 being such that the supply of carbid contained therein will be sufficient to generate the quantity of gas necessary to supply the lights for at least one night, so that the filling of the 45 receptacle 11 may be done in daylight.

The chamber 5 being supported above the bottom 4 of the casing 1, and, in spaced relation to the side walls of the casing 1, is practically surrounded by water, and 50 therefore maintained in a comparatively cool condition, so that the generated gas before reaching the service pipe 6^a is chilled to an appropriate temperature.

When the generator is in operation the 55 valve 32 is open, so that the pressure within the cylinder 26 and within the bell 23 equalizes. When, however, it is desired to refill the container 11 the valve 32 is closed, to that gas already within the bell 23 may not 60 escape into the cylinder 26, and so to the atmosphere when the cap 27 is removed, but pressure within the cylinder 26 may then be relieved by opening the valve 24, after which the cover 27 is unscrewed and the 65 filling is performed as before described. It

is to be observed that the receptacle 11 may be readily lifted from the generator, when the caps 2 and 27 have been removed, and when it is desirable to withdraw from the generator the spent carbid, the container 70 11 is removed, and then by means of any suitable lifter the handle or bail 21 may be engaged and the holder or can 20 lifted out of the generator, so that the spent carbid may be dumped, after which the receptacle or can 20 is replaced and the other parts are put in position as already described, when the generator is in condition to generate gas as before stated. During the filling or cleaning operation it is desirable that there should be no fluctuation in the gas bell, for which reason the gas bell is provided with chains 49 or other flexible strands terminating in hooks 50 which may be engaged over the upper edge of the 75 casing 1, when the cap 2 is removed, thus supporting the bell 23 in an appropriately elevated position.

It will be observed that the removal of the can or container 20 does not result in any 80 contamination of the water within the casing 1 by the spent carbid, nor is there any material withdrawal of water from the casing 1 since the spent carbid forces practically all the water from the can 20, so 85 that the only amount of water which is taken from the container on the withdrawal of the can 20 is the small amount which may be within the can with the spent carbid. For this reason it is only necessary to occasionally supply some water to the generator 90 instead of supplying a comparatively large quantity each time the generator is filled with fresh carbid, and the spent carbid is withdrawn. It will be further observed 95 that the supplemental or emergency supply of carbid is for use only on the exhaustion of the main supply and may be deposited in the main carbid receptacle without the necessity of opening the gas containing portions of the machine or the carbid receptacle itself.

When desirable the generator may be located outside of the building to be supplied and in such case may be buried in the ground so that only the top is exposed or directly accessible, the elongated form of the casing 1 contributing to such arrangement. Under these circumstances the drain valve 46 is provided with an extended manipulating rod 46^a which is accessible near the top of the generator.

What is claimed is:—

1. An acetylene generator comprising a closed casing adapted to contain a body of 125 water, a gas bell in the casing and of a size and axial length to seal in the body of water when in the casing, another bell fast and interior to the first-named bell and of less axial length within the limits of the 130

- first named bell, and a stationary carbid reservoir wholly contained within the second-named bell in position to discharge directly into the body of water forming 5 the water seal for the first-named bell, and the second named bell being provided with a removable top for access to the carbid reservoir.
2. In an acetylene generator, an elongated 10 upright cage, a receptacle for spent carbid adapted to the lower end of the cage, a directing funnel carried by the cage in operative relation to the receptacle for spent carbid, a carbid receptacle adapted to be supported by the upper end of the cage 15 above the receptacle for spent carbid, and a gas bell having a centralized chamber in surrounding relation to the cage and provided with a removable cover, said centralized chamber inclosing the carbid receptacle.
3. An acetylene generator comprising a suitable casing with an interior upright cage, a receptacle for spent carbid adapted to be lodged in the lower end of the cage, 20 a receptacle for unused carbid adapted to be supported at the upper end of the cage, above the receptacle for spent carbid, a funnel or deflector carried by the cage in position to direct spent carbid into the receptacle therefor, a controlling valve or gate for the carbid receptacle, and a gas bell within the main casing and provided with a centralized chamber in surrounding relation to the carbid receptacle, said chamber 25 being provided with a removable cap in position to operate the valve or gate of the carbid receptacle.
4. An acetylene generator comprising a suitable casing with an interior upright cage, 30 a receptacle for spent carbid adapted to be lodged in the lower end of the cage, a receptacle for unused carbid adapted to be supported at the upper end of the cage above the receptacle for spent carbid, a funnel or deflector carried by the cage in position to direct spent carbid into the receptacle therefor, a controlling valve or gate for the carbid receptacle, a gas bell within the main casing and provided with a centralized 35 chamber in surrounding relation to the carbid receptacle, said chamber being provided with a removable cap in position to operate the valve or gate of the carbid receptacle, the inner chamber of the gas bell having 40 valved communicating means with the interior of the gas bell and both the gas bell and interior chamber thereof having valved means for communication with the exterior of each.
5. In an acetylene generator, a gas bell 45 provided with a centralized chamber having a readily removable cover member and extending into the bell toward the lower end thereof for a distance less than the length of the bell, a carbid container lodged within the centralized chamber and removable through the covered end thereof, a stationary support for the carbid container independent of the bells, a receptacle for spent carbid in line with the carbid receptacle and removable through the centralized chamber, and a funnel intermediate of the carbid container and receptacle for spent carbid for directing spent carbid into said receptacle, the funnel being of a size to permit the removal of the 50 receptacle for spent carbid therethrough and having a spread at the wider end greater than the diameter of the centralized chamber.
6. An acetylene generator comprising a gas bell having a removable top, a main carbid receptacle wholly housed therewithin and accessible for the introduction of carbid on the removal of the top of the gas bell, and an auxiliary or emergency carbid receptacle carried by the removable top and 55 accessible for the discharge of its contents into the main carbid receptacle without disturbing the top of the gas bell, said main carbid receptacle being provided with a chamber open at both ends and of a size to receive the auxiliary receptacle on the lowering movement of the gas bell.
7. An acetylene generator comprising an elongated cylindrical casing of substantially even diameter throughout, said casing being 60 permanently closed at the lower end and provided with a removable cap member at the upper end, a cylindrical gas bell within the casing and movable lengthwise thereof, said gas bell having a centralized chamber 65 open at the lower end within the bell and extending above the bell and there provided with a removable cap member, a cage supported by the casing and extending axially thereof into the bell and the centralized chamber thereof, a carbid receptacle supported by the cage within the centralized chamber and removable from the chamber through the upper end thereof and through the upper end of the casing on the removal 70 of the caps therefor, a receptacle for spent carbid adapted to the interior of the cage and normally located below the carbid receptacle, and a funnel carried by the cage between the carbid container and the receptacle for the spent carbid and of a size to permit the withdrawal of the receptacle for spent carbid through said funnel.
- In testimony, that I claim the foregoing as my own, I have hereto affixed my signature 75 in the presence of two witnesses.
